UNITED STATES PATENT OFFICE

BENJAMIN F. CULLISON, OF SHARON HILL, PENNSYLVANIA, ASSIGNOR TO THE TEXAS COMPANY, OF NEW YORK, N. Y., A CORPORATION OF DELAWARE

DESIGN FOR A DISPLAY STAND

Application filed February 26, 1932. Serial No. 43,010. Term of patent 14 years.

To all whom it may concern:

Be it known that I, BENJAMIN F. CULLISON, a citizen of the United States, residing at No. 207 High Street, in the borough of Sharon Hill, county of Delaware and State of Pennsylvania, have invented a new, original, and ornamental Design for Display Stand, of which the following is a specification, reference being had to the accompanying drawings, forming part thereof.

I claim:

The ornamental design for a display stand, as shown.

BENJAMIN F. CULLISON.
